The ornamental design for a mattress cover assembly and brand tag, as shown and described.

DESCRIPTION

FIG. 1 is a front elevational view of the mattress cover assembly and brand tag of the present invention;

FIG. 2 is a rear elevational view of the mattress cover assembly and brand tag of FIG. 1;

FIG. 3 is a left side elevational view of the mattress cover assembly and brand tag of FIG. 1;

FIG. 4 is a right side elevational view of the mattress cover assembly and brand tag of FIG. 1;

FIG. 5 is a top view of the mattress cover assembly and brand tag of FIG. 1;

FIG. 6 is a bottom view of the mattress cover assembly and brand tag of FIG. 1;

FIG. 7 is a perspective view of the mattress cover assembly and brand tag of FIG. 1;

FIG. 8 is another perspective view of the mattress cover assembly and brand tag of FIG. 1, showing the brand tag in an open configuration;

FIG. 9 is a perspective view of a mattress cover assembly and brand tag of the present invention in accordance with an alternative embodiment of the mattress cover assembly and brand tag, and showing the brand tag in an alternative location on the mattress cover assembly; and,

FIG. 10 is another perspective view of the mattress cover assembly and brand tag of FIG. 9, showing the brand tag in an open configuration.

The broken lines in the drawings represent the portions of the mattress cover assembly and brand tag that form no part of the claimed design.
